UNITED STATES PATENT OFFICE.

FRED J. SWANER, OF LOS ANGELES, CALIFORNIA, ASSIGNOR TO ROSE A. SWANER, OF LOS ANGELES, CALIFORNIA.

COMBINED CASEMENT WINDOW, HINGE, AND LOCK.

Application filed February 2, 1925. Serial No. 6,271.

This invention relates to casement windows, hinges and locks.

The general object of the invention is to provide an improved casement window wherein the parts are so constructed that the window can readily be moved to open position, and wherein the window, when desired, may be locked in the closed position.

One of the specific objects of the invention is to provide an improved casement window wherein a hinged mechanism is provided whereby the window may first be raised vertically to clear a window strip after which it may be swung laterally to open position.

Another object of the invention is to provide an improved casement window and hinge wherein the window when closed is weather tight but which may be swung into fully opened position parallel to its closed position and wherein the hinge is arranged so that the window may be entirely removed from the casing without manipulation of the parts of the hinge.

A further object of the invention is to provide a casement window hinge with means built into the hinge for locking the casement window in closed position.

Another object of the invention is to provide a casement window which is hinged to open about a vertical pivot and wherein the initial movement of the window is substantially vertical, together with locking means which will serve to hold the window securely closed, or in an intermediate position for purposes of ventilation.

Other objects of the invention will be apparent from the following description taken in connection with the accompanying drawings wherein Fig. 1 is a front elevation of a casement window embodying the features of my invention; Fig. 2 is a central sectional view through the window showing the latter closed; Fig. 3 is a view similar to Fig. 2 showing the window partly open; Fig. 4 is an elevation partly in section showing the details of the hinges; Fig. 5 is a section taken on line 5-5, Fig. 4, showing the details of the lock; Fig. 6 is a section on line 6-6, Fig. 4; Fig. 7 is a view similar to Fig. 4 showing the parts in another position; Fig. 8 is a development of the upper hinge;

Fig. 9 is a development of the lower hinge; Fig. 10 is a front elevation of one of the hinges and Fig. 11 is a fragmentary detail showing the hinge member on the window. 55

Referring to the drawing by reference characters, I have shown a window frame at 10. This frame is provided with a bottom sill 11 on which a tongue 12 is arranged. The casement window is shown at 14. This window is provided with a sash, the lower portion 15 of which is provided with a groove 16 which fits over the tongue 12. The window 14 at the bottom engages a strip 17 which in conjunction with the tongue and the groove arrangement renders a tight joint and prevents entrance of moisture. The upper end of the window is preferably beveled as at 18, since in operating my window I first move its upper end outwardly so that 60 the groove 16 is free to clear the tongue 12. 65

The means used for supporting the window comprises two members, an upper hinge 20 and a lower hinge 21. The window is provided with a pair of T-shaped lugs 22 which are arranged on a plate to be presently described, the lugs each have a head 23 thereon which is mounted on a stem 24. These lugs engage the hinge members 20 and 21. These hinge members 20 and 21 are each 70 substantially U-shaped and are provided with slots in their opposed faces. 75

A development of the upper window hinge is shown in Fig. 8. This hinge may be made from a single strip of metal 25 as 80 shown. When the hinge is so manufactured the metal is punched with suitable apertures 26 to receive screws for holding it in place. Any number of screws may be used for this purpose and they may be arranged in any 85 desired manner.

The strip 25 is provided with a slot 27. This slot comprises an upwardly inclined portion 28 which merges into a portion 29 inclined slightly downward. A recess 30 is 90 provided adjacent the junction of the portions 28 and 29. The end of the slot terminates in a headed portion 31 through which the heads 23 on the lugs 22 may be 95 inserted. 100

The lower hinge is preferably constructed from a strip of metal 35, shown in Fig.

9. This lower hinge is provided with a slot 36 which includes an abruptly rising portion 37, a gradual rising portion 38, an offset portion 39, a horizontal portion 40, a downwardly inclined portion 41 and a terminal headed portion 42. In constructing the hinges, the strips 25 and 35 are bent to form a U-shaped member after which I prefer to secure top and bottom members on the strips to exclude dust and to present a neat appearance. The hinges may, however, be cast or made in any other desired manner.

The T-shaped lugs 22 heretofore mentioned are secured on plates 45 as shown. These plates are preferably secured to the windows as shown in Fig. 6 and each plate projects a distance beyond the lugs 22 as at 46 to furnish a stop member for the window.

In assembling my device the hinges 20 and 21 are first secured upon the window frame in the desired spaced relation. After this is done, the window is held alongside of the hinges and the lugs 22 are inserted through the slots 31 and 42. The shoulders 50 and 51 serve to hold the window in this position. The operator next grasps the pull 52 and lifting gently, raises the window over the lugs 50 and 51. He will then pull the window forward from the dotted line position shown in Fig. 6, until the heads 23 on the lugs 22 occupy the curved portion 53 (see Fig. 6) of the hinges. The window will remain open in this position due to the slight incline of the slot portions 29 and 41.

To close the window the operator pulls on the pull 52 thus swinging the window about the axis of the lugs 22. This action continues until the lugs are directly below the axial center of the recess 30. When this point is reached, the stem 24 enters the recess 30 and the window is gently raised. The shoulder 30' assists in this action. This raising action lifts the lower lug base over the off-set 39. While the upper lug stem remains in the recess 30 the lower lug moves down the inclined portion 38 of the slot and enters the inclined portion 37. As it does this, the upper lug stem leaves the recess 30 and moves down the slot 29. The abrupt recess 37 causes the groove 16 to pass over the tongue 12 so that the window assumes the position shown in Fig. 7. Further movement of the upper end of the sash brings it to fully closed position.

In opening the window the handle member 52 is pulled first outwardly to move the upper end of the sash to the position shown in Fig. 7, after which the entire sash is raised and simultaneously swung outwardly. On account of the simplicity of construction and the fact that there is practically no friction present, the window can be very easily opened and closed.

In order to lock the window closed, I provide a locking member 61 provided with a

spring pressed plunger 62. This locking member or catch, is shown as mounted on the upper hinge and the plunger is shown as passing through the recess 63 in this hinge. The plate 45 arranged on the window is provided with an aperture 64 which receives the pin 62. When the pin is in the position shown in Fig. 6 it will be apparent that the window cannot be opened until after the pin 61 is withdrawn. By providing another aperture 65 in the plate 45 I may lock the window in the partly open position shown in Fig. 3 by inserting the plunger 62 in the aperture 65.

By referring to Figs. 8 and 9 it will be noted that the ends of the strips 25 and 35 are arranged to be bent along the lines 70, 71 and that the ends 72, 73 are bent against the opposed face of the hinge as shown in Fig. 6. I punch out tongues 75 which are to be bent out and inserted in recesses in the casing and secured by screws 76 as shown.

From the foregoing description it will be apparent that I have provided an improved casement window which is extremely durable, which can be economically manufactured, and which is highly efficient in use and further that along with the features just mentioned, I have provided means for locking the window to prevent unauthorized opening thereof.

Having thus described my invention, I claim:

1. In a device of the class described, a window casing, a casement window, means for supporting said window, said means comprising hinge portions mounted on the casing and second hinge portions mounted on the window, said portions being pivotally connected on a vertical pivot and having coacting parts whereby when the window is opened, it is first lifted and inclined after which it swings outward on its pivot.

2. In a casement window, a casing, and a window, means for hingedly mounting said window about a vertical pivot, said means comprising upper and lower hinge members, each of said members comprising a U-shaped strip of metal having a slot in the wall thereof, one leg of each U being longer than the other and the projecting parts being secured to the window frame, a pair of lugs on the window engaging in said slots and a head on said lugs.

3. In a casement window, a casing, and a window, means for hingedly mounting said window about a vertical pivot, said means comprising upper and lower hinge members, each of said members comprising a U-shaped strip of metal having a slot in the wall thereof, a pair of lugs on the window fitted in said slots, the slot of the upper hinge member being first inclined gradually forward, while the lower slot first rises abruptly.

4. In a casement window, a window casing, a casement window, means for supporting said window, said means comprising hinges including portions mounted on the 10 casing and hinges including second portions mounted on the window, said portions having coacting parts whereby when the window is opened it is first tilted, then lifted after which it swings outward and means 15 to lock said window in fully closed position.
5. In a casement window, a window casing, said casing having a weather strip extending across the bottom thereof and above 20 the sill, a casement window having a groove adapted to fit over said projecting portion, the upper portion of said window being beveled, hinges for supporting said window, said hinges comprising portions mounted on 25 the casing and other portions mounted on the window, said portions having coacting parts whereby when the window is opened it is first tilted, then lifted over said projection after which it swings outward and means to lock said window in closed position.
6. In a casement window, a casing and a window, hinges for pivotally mounting said window on a vertical pivot, said hinges comprising upper and lower hinge members, each of said members comprising a U-shaped strip of metal having a slot in the wall thereof, lugs on the window engaging in 35 said slots, a head on each lug, the slot of the upper hinge being inclined gradually forward, then downward, while the lower slot rises first abruptly then gradually after which it moves downward.
7. In a casement window, a casing and a window, hinges for pivotally mounting said window about a vertical pivot, said hinges comprising upper and lower hinge members, each of said members comprising a U-shaped strip of metal having a slot in the wall thereof, a pair of lugs on the window engaging in said slots, heads on said lugs, said heads each being rounded to fit the base of the U and to turn therein, and a lock for securing said window in position, 45 said lock comprising a spring pressed pin arranged in one of said hinge members, said pin being adapted to engage any one of a plurality of apertures in its companion hinge member which is mounted on the window.
8. In a casement window, a casing and a window, hinges for pivotally mounting said window on a vertical pivot, said hinges comprising upper and lower hinge members, each of said members comprising a U-shaped strip 50 of metal having a slot in the wall thereof, a pair of lugs on the window engaging in said slots, a head on each lug, the slot of the upper hinge member being inclined forward, then downwardly, while the lower slot first 55 rises abruptly and then gradually, after

which it moves downward, there being elongated apertures in said members, adjacent to the ends of the slots whereby the window can be removed.

9. The combination with a casement window, a pair of hinged members constituting upper and lower hinges, each of said hinges comprising a reversely bent strip of metal, said window having headed lugs thereon, a recess in each of said upper and lower 70 hinges in which a post slidably fits, the slot in said upper hinge being inclined gradually to the front, and the slot in the lower hinge being inclined abruptly to the front whereby the window may move outwardly at its upper portion before the lower portion is moved outwardly.

10. In a casement window, a casing and a window, hinges for mounting said window about a vertical pivot, said hinges comprising upper and lower hinge members on the casing, coacting members on the window, each of said hinges comprising a U-shaped strip of metal having a slot in the wall thereof, lugs on the window engaging in 85 said slots, a head on said lugs, the slot of the upper hinge being inclined gradually forward, then downwardly while the lower slot first rises abruptly and later moves downward, there being elongated apertures 90 in one portion of each of said members longer than the head of a lug whereby the window can be removed, and a catch for securing said window in position, said catch comprising a spring pressed pin arranged on 95 said hinge, said pin being adapted to engage in an aperture in one of the coacting members which is mounted on the window.

11. The combination with a casement window of a pair of hinged members constituting an upper and a lower hinge, each of said hinges comprising a reversely bent strip of metal, said window having a headed lug thereon, a recess in said upper and lower members in which said lugs slidably fit, said 100 casing having a tongue and said window having a groove, the slot in said upper hinge member being inclined gradually to the front and the slot in the lower member being inclined abruptly to the front whereby the window may move outwardly at its upper portion to clear the tongue before the lower portion is moved outwardly, the head on the lugs engaging the base of the U when the upper member has moved outwardly so that further outward action of the window brings the lower part outward until the two heads are aligned thus allowing the window to be swung about a vertical 110 axis, said lugs being mounted upon a plate, 115 said plate having projecting portions serving as a stop to limit the outward movement of the window.

12. In a closure for a wall opening, a casing, a closure, means for pivotally mount- 120 125 130

ing said closure upon a vertical pivot, said means comprising upper and lower hinge members, each of said members comprising a U-shaped strip of metal having a slot in the wall thereof, a member on said closure for engaging said U-shaped strips, screws engaging one leg of the U for holding the

hinges in position, outstanding tongues on the other leg of the U, said tongues being adapted to be engaged in notches in the casting. ¹⁰

In testimony whereof, I hereunto affix my signature.

FRED J. SWANER
